MECHANICAL PENCIL

Blanchard Drake Smith, Atlanta, Ga., assignor to
 Scripto Manufacturing Company, Atlanta, Ga.,
 a corporation of Georgia

Application August 17, 1943, Serial No. 498,952

6 Claims. (Cl. 120—18)

1

The invention relates to mechanical pencils and has as an object the provision of a pencil provided with lead propelling and retracting means of such a nature that the lead receiving bore of the pencil will be only slightly larger than the lead itself, whereby to provide support for the lead throughout its length.

A further object of the invention is the provision of a thin clutch operating in slots at diametrically opposite portions of the bore and provided with both propelling and retracting means and means for final expulsion of a lead from the clutch.

A further object of the invention is to provide a pencil having a novel form of lead magazine designed to hold at least two characters of lead either of which may be delivered from the magazine at will.

Further objects will appear from the following description when read in connection with the accompanying drawings, wherein:

Figure 1 is a side elevation of the complete pencil;

Figure 2 is a detail side view partly in central longitudinal section, drawn to an enlarged scale;

Figure 2a is a section similar to Figure 2 showing a different position of parts;

Figure 3 is a detail side elevation of a magazine portion of the pencil, drawn to the scale of Figure 2;

Figures 4, 5, and 6 are further enlarged transverse sections taken on lines 4—4, 5—5, and 6—6, respectively, of Figure 2;

Figure 7 is a still further enlarged perspective view of the propelling mechanism;

Figure 8 is a like view of the clutch; and

Figure 9 is a like view of the magazine control plate.

As shown, the invention embodies a double ended pencil for the carrying of leads of different characters as, for instance, red and blue, soft and hard. The propelling mechanism at each end of the pencil may be of the character of that shown in detail in the drawings.

As shown, the barrel of the pencil is formed with three outer casing parts 10, 11 and 12, which parts may be formed of synthetic plastic. The parts 10 and 12, as shown in connection with part 10, are provided with internal screw-threads 13. A continuously slotted metal sleeve 14 extends within the barrels 10, 11 and 12 and may be continuous throughout the length of the pencil between the points 15 and 16.

Within the sleeve 14 at each end of the pencil, there is shown a slotted tubular member 17 which

2

contains the lead bore and which terminates in a point member 18 having shoulders at the points 15, 16, abutting against the outer barrel portions 10 and 11. The member 17, as will be seen in Figures 4 and 5, is formed with slots 19, 20 at diametrically opposite portions of the lead-receiving bore 21, the slot 20 extending to the surface of the member 17.

Movable in the slots 19 and 20, there is shown 10 the clutch member 22 which is relatively thin and which is provided with the lead receiving jaws 23 extending from each side of a slit 24 terminating in an opening 25 to provide flexibility of the clutch. Coacting with the clutch 22 is the 15 propelling member 26 including a nut, carrying screw-thread segments 27, which member projects through the slot 20 and through the slot of the sleeve 14 into engagement with the screw-threads 13 whereby revolution of the member 17 caused by holding the point 18 and revolving the outer barrel will cause traveling of the member 26 carrying with it the clutch 22 and an engaged lead.

The clutch 22 is shown as formed with a slot 25 30 having an offset providing cam surfaces 31 and 32 at its opening which coact with a lug 33 carried by the member 26. The member 26 is also shown with a laterally projecting shoulder 34 standing normally between the jaws 23 as 30 shown in Figure 2a. In this position of the parts the lug 33 stands between the cams 31 and 32.

In the normal use of the pencil, the lug 33 cannot further enter the slot 30 since the surface 35, underlying the interior of the barrel is prevented 35 by the interior of the barrel 10 from moving outwardly and the member 26 and the clutch 22 must travel together.

Adjacent the point 18 the screwthreads 13 of 40 the barrel 10 are omitted and a tubular member 37 is inserted. The internal diameter of the member 37 is shown as substantially equal to the root diameter of the screwthreads 13, and is at least sufficient to permit an outward movement of surface 35 to bring slot 20 into alignment with lug 33. The inner opening of the member 37 is shown as formed with an annular flange 38 the edge of which aligns with the crests of said screwthreads. The outward movement of the surface 35 occurs when the clutch 22 reaches its 45 outward travel and the lug 33 acting on cam face 31 forces the clutch outwardly and so retains it during the expulsion of the lead by continued advance of the lug 33 in slot 30, and the arrival of the projecting shoulder 34 at the pencil point opening as shown in Figure 2. When the clutch

22 has reached the end of its outward travel, the said portion of the clutch 22 is free to move outwardly into the referred to engagement in the slot 20 and such movement is caused by cam action of the lug 33 upon the cam 31. The clutch 22 thus has its forward travel checked and at the same time is moved outwardly so that the lug 33 aligns with the slot 30 and further movement of the nut 27 acting through the shoulder 34 expels the lead from the clutch, the parts assuming the position shown in Figure 3.

Upon retraction of the nut, the lug 33, striking the cam surface 32, will again move the clutch to the position shown in Figure 2a whereupon a new lead may be inserted to be frictionally grasped by the jaws 23.

The combined thickness of the propelling member 26 and the clutch 22 is less than the diameter of the bore, and the required width of slot for their reception leaves more than 180° of arc of the bore so that the lead which forms a good sliding fit in the bore will be supported throughout its length and therefore colored leads which may be weaker than black leads are better able to support pressure against the points which, except for this support, would cause flexure and possible breakage of the lead.

The magazine portion 11 of the pencil is lined by the sleeve 14 and is divided into two portions by means of a plate 39, an end of which plate 40 is received in a slot 41 at one end of the barrel portion 11.

To provide for flexure of the plate 39 it is slotted by right angular slit 42. The magazine is shown as formed with an elongated opening 43 the width of which is slightly more than the diameter of the lead plus the thickness of the plate 39. The plate 39 is shown as formed with a roughened thumb lug 43' projecting through an opening 44 in the end of the barrel portion 11.

When standing in the central position, the plate 39 prevents egress of leads from either side thereof. When it is forced to one side to the position shown by dotted lines in Figure 6, a lead may escape from the other side of the magazine as indicated by dotted lines in said figure. An indication of the color of lead which may be secured by moving the thumbpiece 43 in either direction is desirably placed upon the exterior of the barrel as shown at 45.

To assemble the pencil structure the partition 39 is inserted into the sleeve 14 and the sleeve and partition are placed in the magazine casing 11. The casings 10 and 12 are then slipped on the sleeve 14 after which the bodies 17 carrying the members 22 and 26 are forced into the sleeve from its opposite ends, the bodies forming a tight fit in the sleeve so as to be not revoluble therein. The margins of the slot in the sleeve 14 being turned to overlie the flattened portion of the slots 20 in the bodies 17 assist in preventing relative rotation between the bodies and the sleeve.

When the bodies 17 are inserted the nut and clutch members occupy the relative positions shown in Figure 2 and during the last part of the insertion the casings 10 and 12 are revolved to engage the nut with the internal screwthreads.

Minor changes may be made in the physical

embodiment of the invention within the scope of the appended claims without departing from the spirit thereof.

I claim:

5. A mechanical pencil structure comprising a cylindrical body member having a marking-element-receiving bore open for protrusion of the element and a longitudinal slot opening to said bore and to the surface of the member; an internally screwthreaded sleeve member surrounding said body member and closing said slot; said members associated for relative rotation; marking element control means slidable in said slot and comprising a propelling portion and a clutch portion in side by side relation; said propelling portion formed with a screwthread element coating with said internal screwthreads and with a shoulder positioned to impinge upon the end of a marking element held by the clutch portion; one of said portions formed with a longitudinal slot with complementary diagonal cam surfaces at an end thereof; the other of said portions carrying a lug normally contacting one of said surfaces; an edge of said clutch portion underlying a part of one of said members to prevent edgewise movement of said clutch portion; the part of said member overlying said edge cut away adjacent the opening of the bore to permit such edgewise movement; and means whereby, at the limit of travel of the control means, edgewise movement of the clutch portion permits entry of the lug into the slot and further travel of the nut portion causes expulsion of the marking element.

20. The structure of claim 1 wherein the part of the member overlying the clutch edge is the inner surface of the sleeve member.

25. The structure of claim 1 wherein the slot formed in the marking element control means is formed in the clutch portion.

30. 4. The structure of claim 1 wherein the cylindrical body member is also formed with a longitudinal slot diametrically aligned with said first named slot and open to said bore with the clutch portion entering both slots.

35. 5. The structure of claim 1 wherein the slot in the body portion terminates short of the marking element protrusion opening.

40. 6. A mechanical pencil structure comprising in combination: a central cylindrical body member formed with a marking-element receiving bore, with a longitudinal slot opening to said bore and to the surface of the body, and with a second slot diametrically opposite the first named slot and opening to said bore; the width of said slots being less than the diameter of said bore; an internally screw-threaded cylinder member surrounding said body member; said members associated for relative rotation; marking-element clutch means mounted to travel in said slots; marking element drive means also traveling in at least one of said slots and having screw thread segments coating with said internal screw threads; and means coating between said drive and clutch means to cause movement of a marking-element gripped by said clutch means.
